UNITED STATES PATENT OFFICE.

JOHN E. LLOYD, OF HOUSTON HEIGHTS, TEXAS.

FLASHING.

1,176,226.

Specification of Letters Patent. Patented Mar. 21, 1916.

Application filed February 24, 1912. Serial No. 679,739.

To all whom it may concern:

Be it known that I, JOHN E. LLOYD, a citizen of the United States, residing at Houston Heights, in the county of Harris and State of Texas, have invented certain new and useful Improvements in Flashing, of which the following is a specification.

My invention relates to new and useful improvements in flashing.

10 The object of the invention is to provide a device of the character described, which is designed to be secured upon roofs and around pipes, which may lead from the interior, through the roof, to the exterior of 15 the house, so as to form a water tight joint between the roof and pipe.

With the above and other objects in view, the invention has particular relation to certain novel features of construction and arrangement of parts, an example of which is given in this specification and illustrated in the accompanying drawings, wherein—

20 Figure 1 is a sectional side elevation of the flashing, showing a section of pipe secured therein, and Fig. 2 is a side elevation thereof.

Referring now more particularly to the drawings, the numeral 1 designates a plate of lead, or other similar material having a central orifice 2, there through, which is surrounded by an upstanding annular flange 3, integral with the plate 1 and having an overhanging annular rim 4 around the upper edge thereof. Alined with the orifice 2 and upstanding from the plate 1, at an angle corresponding to the pitch of the roof, is the sleeve 5, also formed of lead, which is intended to closely surround the pipe and whose upper end may be easily calked in so as to fit closely against the pipe 6 and form 40 a water tight joint therewith, as shown in Fig. 1.

The upper end of the sleeve 5 is surrounded by an annular ring 7, which is dove-tailed into an annular groove surrounding said

pipe and which is composed of solder or 45 some other hard tenacious metal. This ring should be composed of metal much more tenacious than the lead of the sleeve 5 and serves to strengthen the free end of said sleeve and preserve the proper form thereof. 50

In forming this flashing, the plate 1, with its up-standing flange 3 and overhanging rim 4 is first formed and the sleeve 5 is then molded thereon, the ring 7 being secured in the molds so as to form in the metal as said sleeve is being molded and in the process of the formation of the sleeve 5 the same becomes integral with the plate 1 as well as with the ring 7 and the flashing is thus formed into one continuous integral piece. 60

What I claim is:—

A device of the character described composed of a metallic plate having an orifice therethrough to permit the passage of a flue pipe, an annular flange integral with the 65 plate and upstanding therefrom and surrounding said orifice, an annular overhanging bead integral with and carried by the upper edge of the flange, a sleeve whose lower ends surround said flange having an 70 internal annular groove in which said bead fits thereby securing the sleeve to the plate, said sleeve surrounding said orifice and pipe, a ring surrounding the upper end of the sleeve and dove-tailed therein, said ring being formed of tenacious material and reinforcing and preserving the form of the free 75 end of the sleeve, and an inwardly extending flange projecting from the free end of said sleeve and closely surrounding the pipe 80 passing therethrough.

In testimony whereof I have signed my name to this specification in the presence of two subscribing witnesses.

JOHN E. LLOYD.
